UNITED STATES PATENT OFFICE

2,476,273

APPARATUS SENSITIVE TO MAGNETIC FIELDS

Lennox F. Beach, Merrick, N. Y., assignor to Purves Corporation, Springfield, Mass., a corporation of Massachusetts

Application September 17, 1942, Serial No. 458,739

13 Claims. (Cl. 177—351)

1

This invention relates to magnetic field responsive devices and it refers more particularly to devices whose operation depends upon the non-linear magnetic characteristic of a core or cores of permeable material carrying the flux of the field.

Indicating and power controlling devices whose operation depends upon the non-linear or saturation characteristic of iron or the more permeable ferrous alloys are disclosed, and their method of operation described, in U. S. Patent No. 2,047,609 to Haig Antranikian, dated July 14, 1936, and in the copending applications of the present applicant, Serial No. 348,582, filed July 30, 1940, which matured into U. S. Patent No. 2,383,459, issued August 28, 1945, and Serial No. 385,622, filed March 28, 1941, which matured into U. S. Patent No. 2,383,460, issued August 28, 1945, said last application being joint with John C. Purves, and both of said applications being assigned to the assignee of the present invention.

Devices of the character referred to, sometimes known as "flux valves," include an inductor member or a plurality of inductor members, each comprising a core of ferromagnetic material to which a periodically variable magneto-motive force is applied by means of an exciting winding or windings and having an output winding in which an E. M. F. is induced due to the combined action of the exciting flux and the flux of the field in producing periodic saturation of the core. In some instances, a single winding carries both the exciting and output currents. An important application of the flux valve type of apparatus is in the measurement or the indication of the direction of the horizontal component of the earth's magnetic field.

In most flux valve devices the utilized output is an alternating potential at double the frequency of variation of the exciting current and to obtain reliable and accurate operation, particularly at low outputs, it is necessary to eliminate, by balancing or filtering, any component of exciting frequency which appears in the output. To avoid the use of filters, the present invention in certain of its embodiments provides for a simple mechanical adjustment of elements which is effective in balancing out any component output at the frequency of the exciting flux.

Other factors adversely affecting reliability of operation of prior flux valve devices, particularly uniformity of output with repeated occurrence of the same magnetic field conditions, are the existence of a unidirectional magnetic bias in a portion of the inductor core material (which may

2

shift the operating point along the magnetization curve) and an unequal degree of saturation in different portions of such material. Both conditions result from failure to apply the exciting magneto-motive force in a manner which causes all portions of the core material to experience periodic reversals of flux of the same amplitude. The construction of the inductor of the present invention avoids these defects by applying to the inductor core an exciting alternating magneto-motive force producing a nearly uniform flux density throughout the core.

The maximum electrical output of a saturable inductor subjected to a uniform magnetic field is very nearly proportional to the length of the inductor and for a given length the maximum efficiency is obtained by subjecting the entire core material to a uniform degree of saturation corresponding to the most favorable operating point on the magnetization curve. The inductor of the present invention is highly efficient from both these viewpoints since its length is great in proportion to the magnetic material used and the excitation of the core material is uniform throughout and may be adjusted to an optimum operating condition.

Certain magnetic field-sensitive devices have employed an inductor with a "window" or opening through which the exciting or output winding or both must be threaded, which is a tedious and uneconomical manufacturing operation. The construction of the inductor, according to the present invention, is such that all windings may be put on the core elements by ordinary coil winding apparatus without any threading operation, thus reducing manufacturing costs.

It is an object of the present invention to provide a flux valve inductor of simplified construction adapted for economical manufacture.

It is a primary object of this invention to provide a flux valve, or an electrical inductor device, having three core legs of permeable magnetic material, an exciting winding, and pickup coils associated with the respective core legs, the pickup coils being Y connected in a three-circuit alternating output whereby the device will function, through interaction with a unidirectional magnetic field to provide a three-circuit, variable alternating potential output similar to that of a Selsyn transmitter which is adapted to be used in reproducing the position of the core legs in the magnetic field by connecting the output of the device to an induction device of the Selsyn type.

Another object is to provide an inductor which

is highly efficient as to utilization of core material and space occupied for a given output.

Another object is to provide an inductor suitable for applications where space and weight are restricted, such as in gyroscope mounted or gimbal suspended pick-ups.

Another object is to provide an inductor wherein a simple mechanical adjustment may be made to balance out the effect of exciting current on the output.

Another object is to provide an inductor wherein the entire core structure is subjected to a substantially uniform alternating exciting flux thereby increasing the efficiency of the inductor and furnishing a device of stable and reproducible sensitivity.

Another object of the invention is to provide an electrical balancing adjustment in the exciting circuit of a flux valve of the type having a divided core inductor and a divided exciting winding.

A further object is to provide an improved magnetic field-sensitive pick-up suitable for supplying actuating electrical impulses to remote indicating or power controlling devices, or to torque exerting means for precessing a gyroscope.

Still another object is to provide a magnetic compass of the stationary inductor type having improved pick-up means.

Other objects and advantages will become apparent as the description proceeds.

In the figures,

Fig. 1 is a broken view of an improved inductor according to the invention.

Fig. 2 is a sectional view taken along line 2—2 of Fig. 1.

Fig. 3 is a wiring diagram of a single inductor according to the invention, connected to an indicator.

Fig. 4 is a diagrammatic showing of an inductor, adjustable to effect an inductive balance.

Fig. 5 is a wiring diagram of a gyro-stabilized inductor assembly connected to control a remote servo device.

Fig. 6 is an elevation of the stabilizing gyro-vertical of Fig. 5 with the inductor assembly mounted thereon.

Fig. 7 is a perspective view of modified adjustable inductor according to the invention.

Fig. 8 is a section taken transversely of the inductor illustrated in Fig. 7.

Fig. 9 is a diagrammatic view of a pair of crossed inductors according to the invention connected to a crossed-coil indicator.

Fig. 10 is a wiring diagram of the apparatus of Fig. 9.

In the figures, particularly Figs. 1-3, an inductor 10 is shown comprising a pair of elongated core members 11, 12 of equal length and of rectangular cross section positioned parallel to and spaced from one another. These core members may be of "permalloy," "mumetal" or other ferromagnetic material of high permeability, it being particularly desirable to employ material exhibiting a sharp bend or "knee" in the magnetization curve. As an illustration of the size of these core members or strips, in certain successfully tested devices, a thickness of .020" has been used with a width of approximately one quarter of an inch and a length of approximately two inches. Core member 11 is surrounded throughout substantially its entire length by a uniform exciting winding 15 which is adapted to apply a substantially uniform magnetizing force (magneto-motive force per unit distance) along the core axis, while core member 12 is surrounded

by a similar exciting winding 15'. As illustrated, the sections of cores 11 and 12 are uniform throughout their respective lengths and therefore, due to the uniform exciting windings, the same flux density is obtained in all portions of a core at a given instant. If variable section cores are used, the exciting winding may be designed to produce inversely varying magnetizing forces.

Cores 11 and 12 are spaced from one another as by end spacers 16 or other separators of non-magnetic material, although spacers of magnetic material at the ends of the cores, only, may be used to increase the efficiency of the device somewhat. The use of such magnetic spacers, however, has the disadvantage of the possibility of non-uniform sensitivity due to random changes of reluctance of the joints in the magnetic circuit. The separation of the cores is exaggerated in the figures clearly to distinguish the several windings of the inductor.

A pick-up or output winding 17 completely surrounds the assembly of cores 11 and 12 and their respective exciting windings and is preferably symmetrically positioned with respect to the centers of these cores. Winding 17 may or may not extend over the entire length of the cores. A slight balancing adjustment to compensate for inequalities of the two exciting windings may be secured by relatively shifting cores 11 and 12 before secondary winding 17 is put on. However, more efficient balancing arrangements are shown in Figs. 3 and 4, to be described.

In the wiring diagram of Fig. 3 exciting windings 15 and 15' are connected in series and in a manner to produce magneto-motive forces in opposite directions in cores 11 and 12 when connected to the same source of alternating potential 20, as by way of potential divider 21. A potentiometer 22 having an adjustable contact 23 is provided for equalizing the excitation of the two cores, equalization being evidenced by the absence of a component at exciting frequency in the output of coil 17. Output coil 17 is connected to a phase detector or phase-sensitive modulator 25 which is biased by an alternating potential supplied from source 20 by way of frequency doubler 26.

It is known in the operation of flux valve devices that the phase of the alternating output potential reverses when the direction of the field reverses with respect to the normal to the magnetic axis of the inductor member. To detect this phase change and obtain a unidirectional potential reversing in polarity in correspondence therewith, any one of a number of phase sensitive devices known in the art may be employed. One such device is illustrated in the above referred to application No. 348,582, now U. S. Patent No. 2,383,459.

Frequency doubler 26 in the A. C. biasing circuit of device 25, which may be of conventional known design, is included since the utilized electrical output of the flux valve is at double the frequency of the exciting supply. A suitable indicator such as zero-center D. C. meter 27 is connected to the output of phase detector 25 to indicate the direction and magnitude of the magnetic field.

Inductor 10, used as a compass, may be mounted directly on a mobile craft such as an airplane, in which case by orienting inductor 10 with its magnetic axis perpendicular to the longitudinal axis of the craft zero center meter 27 may be caused to indicate the magnetic heading of the craft or the inductor may be mounted on a rotat-

able support 28 (Fig. 3) and manually positioned to give a null or a maximum indication on meter 27, the direction of the field being perpendicular to the inductor axis if the null indication is used and parallel to said axis if the maximum indication is used. Support 28 may also be caused to be self-orienting by means similar to those disclosed in my aforementioned application Serial No. 348,582, now U. S. Patent No. 2,383,459.

In Fig. 4 an arrangement is illustrated which dispenses with the balancing potentiometer 22 of Fig. 3 by providing a pair of core members 11, 12' of unequal length. As before described, each core carries a uniformly wound exciting winding, as 15, 15', which extends over substantially the entire length of the core. When core 12' is symmetrically positioned with respect to the center of core 11 and magnetic conditions are uniform throughout the two cores, no output component at exciting frequency will appear in winding 17. To locate this central position or rather to effect an inductive balance that compensates for any slight magnetic irregularities which may cause an exciting frequency component to appear in the output when winding 17 is geometrically symmetrical with respect to windings 15 and 15', core 12' may be shifted axially with respect to core 11 until such inductive balance with respect to winding 17 is obtained.

This adjustment may be made before output coil 17 is wound over the cores 11, 12' by slipping an exploring or test coil over the cores and, with the cores normally excited, making a suitable axial adjustment to reduce the exciting frequency component in the test coil voltage to zero, then immobilizing the two cores relative to one another, removing the test coil and applying output winding 17. Alternatively the output coil, and also if desirable the exciting coils, may be wound on supports which are slidably adjustable with respect to the cores and the members of the assembly fixed in position after a balance is reached.

In Fig. 5, there is shown a combination of three inductors 30, 31 and 32, preferably of the previously described construction, positioned with their respective magnetic axes, at equal angles one to another in a plane to form a pick-up device 35 mounted on a stabilizing gyro-vertical 33. Device 35 supplies a three-component electrical output adapted to actuate a remote receiver 36 of the "selsyn" type. Receiver 36 comprises a three winding stator 31 and a single winding rotor 38 and is operated as a constrained rotor device, sometimes referred to as a "signal generator" or "synchro transformer." Receiver 36 is connected to furnish a single phase alternating potential signal to an amplifier 40, which may be of conventional design, whose output operates a motor 41 to position a device 42 in relation to the direction of the magnetic field actuating pick-up 35. A repeat-back connection 42 to rotor 38 of "selsyn" 36 is provided by shaft 45 geared to the motor shaft.

Gyro verticals such as 33, are well known devices employing gravity controlled erection means, as 48, to maintain the spinning axis of a gyro in a vertical position. By a suitable mounting on a gyro, the assembly of inductors 30, 31 and 32 may be stabilized in a selected plane as, for example, the horizontal, the inductor outputs being proportional to components of the magnetic field in said plane. When stabilized in the horizontal plane, as in a compass pick-up, the out-

puts from the three inductors are proportional to three symmetrical components of the horizontal component of the earth's magnetic field. In addition to its use as a compass pick-up, the described plane assembly of a plurality of inductors finds numerous other applications including the fields of the stabilization of aircraft, sensitive instrument repeaters, etc.

Instead of operating motor 41, the output of amplifier 40 may be used to actuate torque exerting means for precessing a directional gyroscope to a position corresponding to the direction of the earth's field, to which pick-up 35 is subjected. Such an arrangement, utilizing inductors of a different type, is shown in my copending application Serial No. 414,422, filed October 10, 1941, joint with O. E. Esval and others, which matured into U. S. Patent No. 2,383,461, issued August 28, 1945.

Figs. 7 and 8 illustrate a modification of the inductor of the invention in which an inductive balance between the two primary exciting windings and the output winding is obtained by differentially changing the number of turns of a continuous conductor constituting the primary windings. In this modification, cores of cylindrical form are preferably used, as 50, 51, rotatably mounted on a frame 53. A continuous conductor oppositely wound on the two cores has different portions forming the two exciting windings 54 and 55 therefor. A terminal of this continuous conductor is fixed on each of the cores and connections brought out to an external circuit by way of contact members 57, 58 and respectively cooperating brushes 59, 60. Surrounding the two cores is output coil 67 wound on a supporting frame 68. Due to the opposite winding of the primary coils 54, 55, these coils are oppositely inductively related to coil 67.

Cores 50 and 51 are prevented from free rotation by the friction of their bearings in frame 53, a screw driver adjustment, such as slots 63, being provided for rotating one core or the other to effect an inductive balance. A balance is made by supplying alternating current to windings 54 and 55 by way of brushes 59 and 60 and contact members 57, 58 to produce a selected degree of saturation in cores 50, 51 and by connecting indicating means to coil 67, sensitive to the exciting frequency component which appears in that coil due to unequal mutual inductances between coil 67 and coils 54 and 55, respectively. An adjustment is then made by rotating one or the other of cores 50, 51 until such exciting frequency component is reduced to zero or minimum. It will be apparent that counter-clockwise rotation of core 50, for example, causes a simultaneous increase of the number of turns in coil 54 and a decrease of the number of turns in coil 55, thereby differentially altering the mutual inductances of said two coils with respect to coil 67 in one direction, while similar rotation of core 51 differentially alters the mutual inductances in the opposite direction.

Fig. 9 shows a combination of a pair of crossed inductors, of the improved construction disclosed herein, and a crossed coil indicator in which the two pick-up or inductor output coils are switched in rapid alternation to corresponding indicator coils, thus rendering the device operative along only one inductor axis at a time. The pick-up 73 is shown as comprising inductors 70 and 71 positioned with their magnetic axes at right angles to one another for supplying outputs 75 respectively proportional to relatively perpen-

dicular components of a magnetic field while the indicating device 78 is shown as comprising a pair of stationary coils 74 and 75 likewise positioned with their magnetic axes perpendicular with one another and a permanent magnet 76 mounted on a vertical spindle passing through the intersection of the axes of coils 74, 75 for actuation by said coils to a position corresponding to the direction of said field.

A pointer 77 (shown, for clearness, at a angle to the magnet) is mounted above magnet 76 on the magnet spindle for indicating bearings on a graduated card 79.

The switching means is better seen in the wiring diagram of Fig. 10. Vibrator 80 has its exciting coil 81 connected to D. C. source 83 in series with exciting windings 85 and 86 of inductors 70 and 71 respectively, here illustrated as parallel connected. It will be understood from the description of the preceding figures that each winding 85, 86 has portions oppositely wound on two spaced cores, one above the other, corresponding to windings 15 and 15' of Fig. 1.

Excitation of coil 81 attracts an armature 88 which eventually engages contact 89 and short circuits coil 81, thereby deenergizing said coil and permitting armature 94 to return to its unoperated position. The repetition of the described cycle of events which includes the short-circuiting of coil 81 causes a pulsating unidirectional current to flow in windings 85 and 86 for saturating inductors 70 and 71 and rendering them sensitive to a magnetic field. Output windings 93 and 94 of inductors 70 and 71, respectively, have a terminal of each connected to junction point 95, connected by lead 96 to phase-sensitive amplifier-modulator 100 of known design. The opposite terminals of windings 93 and 94 are connected to vibrator contacts 97 and 98 respectively. A rocker arm 102 rotated in correspondence with, and about the pivot point of, armature 88 carries a pair of contact arms 103, 104 insulated from armature 88 and from each other. Arm 103 is adapted upon displacement from its unoperated position to make contact with one of contacts 97, 98 and is connected by lead 106 to the input of amplifier 100. Oscillation of arm 103 therefore serves to switch windings 93 and 94 alternately to the input of amplifier 100 in synchronism with the pulsations of exciting current produced by the short-circuiting of vibrator coil 81.

Contact arm 104, connected by lead 105 to the output of amplifier 100, upon oscillation by rocker 102 makes contact in alternation with contacts 107 and 108 which connect with terminals of coils 74 and 75 of indicator 78, respectively. The opposite terminals of these coils 74 and 75 are joined at a common point 109 and connected through a common lead to the output of amplifier 100. Oscillation of arm 103 therefore serves to switch the output of amplifier 100 to indicator coils 74 and 75 in synchronous alternation with the switching of coils 93 and 94 to the input of the amplifier, coil 93 being connected to the amplifier input circuit when coil 74 is connected to the output and similar correspondence obtaining between coils 94 and 75.

An additional contact arm 110 in electrical connection with arm 88 and operated therewith may be employed in cooperation with a contact 111 to supply interrupted current from source 83 over leads 112 to amplifier-modulator 100 to render this device sensitive to the phase of the input potential thereto.

Amplifier-modulator 100 is a phase-sensitive device, such as device 25 of Fig. 3, of a type well known in the art, which supplies a unidirectional output whose polarity reverses with reversal of the phase of an input alternating potential. Such circuits require a source of reference phase. By the described arrangement of contacts on a single vibrating element the alternating components of the inductor exciting current and the current supplied over leads 112 are of the same frequency and maintain a constant phase relationship. I have found that the current supplied over leads 112 may be used directly to render amplifier 100 phase sensitive. However, since the outputs of pick-up coils 93, 94 is at double the exciting frequency, the apparatus designated generally by the block 100 preferably includes means for doubling the frequency of the alternating component of the supply by way of leads 112.

Since the moving system of indicator 78 has a certain amount of inertia, magnet 76 and pointer 77 will provide a steady indication of the resultant of the fields set up in coils 74 and 75 by the direct current output of amplifier 100 if vibrator 80 operates at a sufficiently high rate. The position of pointer 77 may be read on graduated card 79.

Among other advantages, the arrangement of Figs. 9 and 10 uses the same amplifying elements to supply current to coils 74 and 75 and thereby eliminates errors due to differential amplifier changes in a system of the type described. Vibrator 80 may be of simple design such as is used in plate supply circuits for automobile radio sets and the current supplied over leads 112 may furnish plate current for amplifier 100. The circuit being operated entirely from a D. C. source finds many applications where alternating potentials are not available.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim and desire to secure by Letters Patent is:

1. In apparatus sensitive to an external magnetic field for supplying a voltage output dependent in magnitude upon the direction of said field relative thereto, an inductor comprising a pair of elongated laterally spaced magnetic core members of unequal length, a source of alternating potential, a winding on each of said members connected to said source, each of said windings being constructed and arranged to apply a uniform magnetizing force along substantially the entire length of the core member with which it is associated and a third winding surrounding both of said core members, said members being relatively positioned to produce equal and opposite mutual inductance between the respective exciting windings thereupon and said third winding said third winding being adapted to supply as an output a potential induced therein through interaction between said inductor and the external field.

2. In a device sensitive to an external magnetic field for supplying a voltage output depending in magnitude upon the direction of said field relative thereto, a pair of spaced core members of permeable, magnetic material, a continuous con-

ductor having portions thereof coiled about each of said core members, said conductor being arranged and adapted to produce, when energized from a source of periodically varying current, a periodically varying flux flowing in relatively opposite directions in said core members, respectively, for instantaneous values thereof, adjustable means for simultaneously uncoiling said conductor from one member of said pair and recoiling it about the other member, connecting means for supplying current to said conductor from a source of periodically varying current, and a pick-up winding surrounding both of said core members whereby potentials of a frequency equal to the periodicity of said varying flux will be substantially balanced out in said pick-up winding while alternating voltages produced through interaction between said device and external field and of a frequency twice that of the periodicity of the flux variations will be provided as a signal output by said pick-up winding.

3. In a device sensitive to an external magnetic field for supplying a voltage output dependent in magnitude upon the direction of said field relative thereto, an output coil, a frame, a pair of cores of magnetic material laterally spaced within said coil, each rotatably mounted on said frame, a continuous conductor having portions thereof wound in opposite directions on said cores to form oppositely acting exciting windings for producing flux flowing in opposite directions for instantaneous values thereof in said cores and having terminals thereof fixed respectively on said cores, a source of alternating current, and connecting means for supplying current to said conductor from said source, simultaneous rotation of said cores in opposite directions with the accompanying differential change in the number of turns in said windings providing an adjustment of the voltage induced in said output coil by current in said conductor whereby potentials of a frequency equal to that of said alternating current source will be substantially balanced out in said output coil while alternating voltages produced through interaction between said device and external field and of a frequency twice that of said alternating current source will be provided as a signal output by said output coil.

4. In a device sensitive to an external magnetic field for supplying a potential output dependent in magnitude upon the direction of said field relative thereto, an inductor comprising a pair of laterally spaced, elongated core members of permeable magnetic material, an exciting coil on each core member, said exciting coils being so constructed and relatively arranged as to produce, when energized from a source of pulsating electrical energy, periodically varying flux flowing in instantaneously opposite directions in said core members, respectively, a pick-up winding comprising convolutions each encircling both of said core members, and means for differentially varying the components of voltage induced in said output coil by the currents in said exciting coils whereby potentials of a frequency equal to the periodicity of said varying flux will be substantially balanced out in said pick-up winding while alternating voltages produced through interaction between said device and an external field and of a frequency twice that of the periodicity of said flux will be provided as a signal output by said pick-up winding.

5. In a device sensitive to an external magnetic field for supplying a potential output dependent in magnitude upon the direction of said field

relative thereto, an inductor comprising a pair of laterally spaced, elongated core members of permeable magnetic material, an exciting coil on each core member, said exciting coils being so constructed and relatively arranged as to produce, when energized from a source of pulsating electrical energy, substantially equal periodically varying fluxes flowing in instantaneously opposite directions in said core members, respectively, a pick-up winding comprising convolutions each encircling both of said core members, and means for differentially varying the inductance between said exciting coils and said output coil whereby potentials of a frequency equal to the periodicity of said varying flux will be substantially balanced out in said pick-up winding while alternating voltages produced through interaction between said device and an external field and of a frequency twice that of the periodicity of said flux will be provided as a signal output by said pick-up winding.

6. In a device sensitive to an external magnetic field for supplying a potential output dependent in magnitude upon the direction of said field relative thereto, an inductor comprising a pair of parallelly extending core members of permeable magnetic material, said members being of unequal length, means for producing a periodically varying flux flowing in relatively opposite directions in said core members, respectively, for instantaneous values thereof, and a pick-up winding comprising convolutions each encircling both of said core members whereby potentials of a frequency equal to the periodicity of said varying flux will be substantially balanced out in said pick-up winding while alternating voltages produced through interaction between said device and an external field and of a frequency twice that of the periodicity of said flux will be provided as a signal output by said pick-up winding.

7. In a flux valve of the character described for supplying a potential output dependent in magnitude upon the direction of an external magnetic field relative thereto, an inductor comprising a pair of laterally spaced, elongated core members of permeable magnetic material so relatively arranged that a first thereof extends axially beyond the second at an end thereof, means for causing exciting fluxes to circulate through said inductor, and a pickup winding having convolutions extending about both core members.

8. In a flux valve of the character described for supplying a potential output dependent in magnitude upon the direction of an external magnetic field relative thereto, a magnetic circuit including means for causing exciting fluxes to circulate thereabout and two core portions of permeable magnetic material arranged on opposite sides of said circuit so that respective exciting fluxes in said core portions flow simultaneously in opposite directions, said circuit being so constructed and said core portions being so relatively arranged as to provide a leakage flux predominately of one of said directions of flow, and a pickup winding at least initially movable relative to at least one of said core portions and having its convolutions extending about both thereof whereby the relative relation of said pickup winding to said leakage flux may be adjusted to reduce the voltage component of exciting frequency in the pickup winding.

9. A flux valve for use in a remote reading compass system comprising three relatively angu-

11

larly disposed inductors each including a pair of laterally spaced, elongated core members of permeable magnetic material, means for producing a pulsating flux in the core members of each inductor, said flux flowing in the members of each inductor in respectively simultaneously opposite directions, and pick-up windings associated with each inductor and respectively comprising convolutions each encircling both core members of the inductors whereby potentials of a frequency equal to the periodicity of said varying flux will be substantially balanced out in said pick-up windings while alternating voltages produced through interaction between said inductors and an external field and of a frequency twice that of the periodicity of said flux will be provided as a signal output by said pick-up windings, the pick-up windings of the inductors being connected together in polyphase fashion.

10. A flux valve for use in a remote reading compass system comprising three relatively angularly disposed inductors each including a pair of laterally spaced, elongated core members of permeable magnetic material, a coil on each core member adapted when energized from a source of periodically varying electrical energy to produce periodically varying flux in said core members, said flux flowing in said members in respectively, simultaneously opposite directions, and pick-up windings associated with each inductor and respectively comprising convolutions each encircling both core members of the inductors whereby potentials of a frequency equal to the periodicity of said varying flux will be substantially balanced out in said pick-up windings while alternating voltages produced through interaction between said inductors and an external field and of a frequency twice that of the periodicity of said flux will be provided as a signal output by said pick-up windings, the pick-up windings of the three inductors being Y connected together across a three terminal output.

11. A flux valve of the character recited in claim 9 in which the pick-up windings are Y connected together across a three terminal output.

12. An electrical inductive device for producing through interaction with a unidirectional magnetic field a three-circuit, variable alternating potential output and in which the alternating E. M. F. in each circuit varies with the orientation of the device in the magnetic field, said device comprising an inductor having three core legs of permeable magnetic material equi-angularly disposed with respect to one another in triangular fashion, coil means associated with said inductor and adapted to be connected with a source of single phase alternating current for producing periodically varying fluxes in said cores, and a pick-up coil associated with each core leg for generating varying potentials under the influence of said external field upon said core legs, said pick-up coils being Y connected in a three-circuit alternating output similar to that of a Selsyn

12

transmitter, whereby the output of said coils may be used to reproduce the position of said inductor in said magnetic field by connecting said output to an induction device of the Selsyn type.

13. An electrical inductive device for producing through interaction with a unidirectional magnetic field a three-circuit, variable alternating potential output and in which the alternating E. M. F. in each circuit varies with the orientation of the device in the magnetic field, said device comprising an inductor having three substantially coplanar core legs of permeable magnetic material equi-angularly disposed with respect to one another in triangular fashion, coil means associated with said core legs and adapted to be connected with a source of single phase alternating current for producing periodically varying fluxes in said core legs, and a pick-up coil associated with each core leg for generating varying potentials under the influence of said external field upon said inductor, said pick-up coils being Y connected in a three-circuit alternating output similar to that of a Selsyn transmitter in which the generated potentials are of double the frequency of said source, whereby the output of said coils may be used to reproduce the position of said inductor in said magnetic field by connecting said output to an induction device of the Selsyn type supplied with double the frequency of said source.
